UNITED STATES PATENT OFFICE.

JOHN HENDERSON DARROW, OF RED LODGE, MONTANA.

REINFORCED-CONCRETE CULVEET.

1,182,872.

Specification of Letters Patent.

Patented May 9, 1916.

Application filed June 19, 1915. Serial No. 35,007.

To all whom it may concern:

Be it known that I, JOHN H. DARROW, a citizen of the United States, and a resident of Red Lodge, in the county of Carbon and State of Montana, have invented a new and Improved Reinforced-Concrete Culvert, of which the following is a full, clear, and exact description.

My invention relates to culverts of the sectional type, and has reference more particularly to reinforced-concrete culverts in which the section joints are staggered.

The object of the invention is to provide a simple, inexpensive, and efficient culvert formed of upper and lower concrete sections, the joints of which are staggered and the reinforcement of which sections is utilized as means for detachably securing the upper and lower sections.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a side elevation of culvert sections partly sectionalized to show the details of construction; Fig. 2 is a cross section through the culvert on line 2—2, Fig. 1; and Fig. 3 is a perspective view of the culvert sections showing the upper sections removed to illustrate the reinforcing means which serve the purpose of a locking device for the sections.

Referring to the drawings, each of the culvert sections is preferably in the shape of a U channel 5 reinforced adjacent the ends by U-shaped irons 6, the ends 7 of which project out of the longitudinal edges of the sections a length sufficient to project through the sides of the coöperating sections. The longitudinal edges of each section have a central depression 8, the ends of which depression are preferably beveled, as shown at 9, and the length of which depression is substantially twice the length of the end portion 10 of each section, so that two portions end to end will have their end portions 10 at the longitudinal edge to fit snugly into the recess 8 of the underlying or superposed section. Each of the sections, in addition to being reinforced by the

U-shaped irons 6, is reinforced by tubular members 11 located in the sides of the channeled section within the recesses 8. These tubular members form sockets for the end 60 7 of the U iron 6. The ends of the tubular sections 11, at the bottom of the sections, lie in a recess 12 whereinto the threaded extremity of the end 7 projects to receive a nut 13 which bears on to the end of the tubular member 11 and serves as a washer for said nut in addition to being a socket for the end 7.

It will be noted from Figs. 2 and 3 that when the upper and lower sections are interconnected the joints of the sections are staggered and each of the recesses 8 of each section engages the end projections 10 of the sections coöperating therewith. This engagement of the recesses with the end projections prevents any longitudinal displacement of the sections relative to one another, which tendency is further resisted by the locking means formed by the nuts 13 at the ends of the U-shaped irons 6. A lateral displacement of the sections is prevented by said reinforcing members 6 and 11 which form the means for locking the sections together.

While I have described the principle of operation, together with the device which I now consider to be the best embodiment thereof, I desire to have it understood that the device shown is merely illustrative and that such changes may be made as are within the scope of the appended claims.

I claim:

1. A reinforced-concrete culvert consisting of a plurality of sections, each of channeled cross section, U-shaped irons reinforcing the sections at the ends thereof with the ends of the irons projecting above the longitudinal edges, each of said sections having a depression in the longitudinal edges thereof between the projecting ends of the 100 U-shaped irons, tubular members in the side of the channeled member within the recess of the longitudinal edges for engaging the projecting portions of the U irons of a coöperating section, and locking means associated with the projecting ends of the U-shaped irons.

2. A reinforced-concrete culvert consisting of a plurality of coöperating sections each of channeled cross section, reinforcing members adjacent the ends of the channeled sections projecting above the longitudinal

edges thereof, each of said sections having a recess in the longitudinal edges thereof between the members, tubular members in the sides of the sections within the recess and projecting through the bottom of the section for engaging the projecting ends of the U iron of a coöperating section, said sections having recesses at the bottom thereof where the tubular members project, and locking means associated with the ends of the reinforcing members.

3. A reinforced-concrete culvert consisting of a plurality of coöperating sections each in the shape of a U-shaped channel, U-shaped irons reinforcing the sections at the ends thereof with the ends of the irons projecting above the longitudinal edges of the sections, each of said sections having a recess in each of the longitudinal edges thereof between the projecting ends of the irons, tubular members in each side of the sections located within the recess of the sides, said tubular member forming sockets

for the projecting ends of the irons, said tubular members projecting through the bottom of the sections, said sections having a recess at the bottom thereof where the tubular members project, and a nut threaded on to the projecting ends of the irons.

4. A reinforced-concrete culvert consisting of a plurality of sections each of channeled cross section, reinforcing bars for said sections projecting above the longitudinal edges of the sections, tubular members reinforcing the sections for engaging the projecting parts of the reinforcing bars of coöperating sections, and locking means associated with the projecting ends of the bars.

In testimony whereof I have signed my name to this specification in the presence of two subscribing witnesses.

JOHN HENDERSON DARROW.
